CLAIM

The ornamental design for a camera, as shown and described.

DESCRIPTION

FIG. 1 is a perspective view of a camera showing our new design;

FIG. 2 is a front elevational view thereof;

FIG. 3 is a left side elevational view thereof;

FIG. 4 is a top plan view thereof; and,

FIG. 5 is a bottom plan view thereof.

Portions in broken lines are for illustrative purposes only and form no part of claimed design.
